UNITED STATES PATENT OFFICE.

ERNEST ALBERT NORMAND, OF SAN FRANCISCO, CALIFORNIA, ASSIGNOR, BY DIRECT AND MESNE ASSIGNMENTS, OF ONE-HALF TO EMILE H. NORMAND, OF SAN FRANCISCO, CALIFORNIA, AND ONE-HALF TO EVERETT R. CARPENTER, OF WASHINGTON, DISTRICT OF COLUMBIA.

PAPER-FOLDING APPARATUS.

1,046,325.

Specification of Letters Patent.

Patented Dec. 3, 1912.

Application filed January 5, 1901 Serial No. 294,809.

To all whom it may concern:

Be it known that I, ERNEST A. NORMAND, a citizen of the United States of America, and a resident of the city and county of San Francisco, in the State of California, have invented certain new and useful Improvements in Paper-Folding Apparatus, of which the following is a specification, reference being had therein to the accompanying drawings.

This apparatus is especially designed for the purpose of doubling up loose sheets of paper alternately in opposite directions and placing the same in suitable positions for interleaving.

The invention contemplates the putting up of toilet and other paper in the form of books or packages composed of loosely-interleaved sheets and adapted to be placed in a slotted container with the top or first leaf projecting out therefrom, so that by pulling on the projecting leaf it will operate to draw out the first sheet and at the same time cause the first leaf of the second sheet to project in its place, and so on leaf after leaf and sheet after sheet till the container is emptied, the paper therein in the meanwhile being properly shielded and capable of use with the greatest possible economy.

Such books or packages can be made most expeditiously and with the least expense by interfolding the paper off the rolls as they come from the mill and subsequently cutting it up of the required length, as many webs being employed, whenever feasible, as will yield the desired number of sheets in each book or package.

Various schemes and devices have been suggested and proposed for producing the like, but in so far as this inventor is aware they have not proved satisfactory for tissue and other easily torn paper, because of the custom that has prevailed of attempting to carry on the interfolding operation simultaneously with the folding of the individual webs, which manner of proceeding causes incessant friction resulting in the frequent tearing and parting of the paper, and consequent stoppage of the machinery, the working whereof therefore is too slow to be commercially remunerative.

The present invention provides for the

complete isolation, and proper guidance, of each single web of paper while it is being folded, so that, whatever may be the tension of the individual web it cannot in the least degree affect or be affected by the adjacent ones, and the webs do not come together to be interleaved until after they have been drawn through and out of the apparatus.

The structural details of this improved apparatus will now be succinctly described, and the novel features thereof further pointed out.

In the accompanying drawings, Figure 1 is a top plan of a small form of the apparatus. Fig. 2 is a central longitudinal section of the same. Fig. 3 is an enlarged perspective view, showing one of a number of tubes comprised in the apparatus. Fig. 4 is a partial cross section on the line A—A of Fig. 1, also enlarged. Fig. 5 is a similarly-enlarged top view of a corresponding fragment of the apparatus, at the entering end of its tubes. Fig. 6 is a transverse section on the line B—B of Fig. 1, enlarged to the scale of Figs. 4 and 5. Fig. 7 is a similar section on the line C—C of Fig. 1, with the bends and curves thereof rather exaggerated. Fig. 8 is a diagrammatic view, illustrating in perspective the (approximate) shape given to the several tubes at the delivery end of the apparatus, and the folds thereby produced in webs of paper that are passed through the respective tubes, preparatively to interleaving. Figs. 9 and 10 are likewise diagrams, representing respectively the entrance and delivery ends of tubes of modified construction.

The same reference-characters, wherever they occur, designate the same parts throughout the various figures.

The apparatus consists principally of two series of tubes, or conduits 1 and 2, oppositely faced and laid one on top of the other upon some suitable support, as a table or frame 3. Fig. 3 illustrates the preferred form of the said tubes, when the same are made of sheet-metal, which form is identical for both series, the only difference between the two series being one of position. As represented in this view, each tube is flat at one end, and for a short distance there-

- from, or as far as the point marked 4, whence the tube is gradually creased outward, on a median line, as at 5, till it is almost doubled upon itself at the other end.
- 5 A correspondingly-shaped channel or passage, flat at its incipiency, thence sloping from the center to opposite sides, by degrees and more and more as it advances, and finally taking an approximately ogival bend,
- 10 is thereby produced, which, it will be readily understood, is adapted to impart the same form to a web of paper passing therethrough,—the paper entering in a flat state and being doubled over as it comes out.
- 15 In the construction illustrated by Figs. 1 to 8, inclusive, each tube (1 or 2) is left open, as at 6, on the inwardly-creased side, the longitudinal slot-like aperture thus formed serving chiefly to economize material, when the tube is made of metal,—brass, for instance. This aperture is covered, whenever the apparatus is being used, by means of a strip 7, of pliable material, as stout paper or fibrous board or stiff leather,
- 25 which is of substantially the same width as the inside of the tube and is inserted therein, with the paper to be folded, the strip remaining in the tube to continue to guide the paper through, after insertion. Spare strips (7) are provided, which may be termed "emergency" strips, from the fact that they do not come into use unless breaks occur in the paper that is being folded, within the tubes, when it becomes necessary to re-insert the paper and again pull it completely through.
- 30 The inserted strips are made to project slightly outward where they enter each tube, the mouth whereof is moreover provided with a curved lip 8, for the common purpose of properly guiding in the paper to be folded. The tubes of the two series 1 and 2 are oppositely faced, as aforesaid, in the sense that their open or slotted walls are turned toward one another. They are not, however,
- 35 set squarely face upon face, but are arranged so as to break joints at their entering-ends, as suggested in Fig. 9, and to intermesh or interlock at the opposite creased ends, as Figs. 7, 8, and 10 respectively indicate.
- 40 This arrangement causes the several tubes to converge toward a common center at their delivery ends while spreading out in the arc of a circle at the entrance ends, the whole having a fan-like appearance as seen in Fig. 1. As before intimated, the paper to be folded is preferably supplied to the apparatus in continuous webs previously wound into rolls 9, as commonly sold. One
- 45 such roll is provided for each tube, the same being mounted in suitable brackets or uprights, as 10. No particular disposition of the rolls or webs is required, other than what may be found most convenient in each case to lead the paper to its own part of the apparatus. The alinement of the rolls and

uniform elevation of the webs shown in the drawings for each series of tubes are therefore rather immaterial.

It will be observed that although each web of paper is kept entirely separate from any of the others while being drawn into and out of the apparatus, the several webs are so folded during their passage through the same, that they become interleaved the moment they emerge therefrom. This is clearly illustrated in Fig. 8, wherein it will be seen that the folded webs issuing from the upper tubes 1 virtually fall astride of the adjoining halves of the relatively-inverted webs that come out of the lower tubes 2. The webs passing through these upper and lower tubes are respectively marked 11 and 12 in the accompanying drawings.

Collectively, the webs 11 and 12, as they are being drawn away from the apparatus, form a long bundle, which upon being cut into the usual lengths or sections will yield a greater or less number of books or packages, naturally containing each as many interleaved sheets as there are tubes employed in the apparatus, the latter easily including from twenty-five to fifty and more. Books or packages of this character vary in size according to the nature of the paper of which they are made and the use to which they are destined, depending, for example, on whether the paper is of the kind required to make cigarettes, or is to be used for toilet purposes, or for wrapping jewelry, candies, fruit and confections, etc., and whether also it is to be given away with small purchases of tobacco or as advertising matter, or sold for carrying in the pocket or for use at home or on a store counter. They may, therefore, be composed of any desirable number of sheets, say from twenty-five to one thousand. The thicker books or packages are obtained by placing together, side by side, two or more bundles of the interleaved webs, causing the adjacent sheets of adjoining bundles to be similarly interleaved, and then cutting up the juxtaposed bundles to make the books or packages of the required dimensions. As a convenience in counting and handling the bundles for producing books or packages of a prescribed thickness, to either add to or take from the same, the outer leaf of the first sheet, on either side of each bundle, is preferably made to project above the rest, in order that it may be quickly seen and easily reached. This is best accomplished by making the first tube, on either side of the apparatus, so that the outer half thereof will stand above the other tubes, as indicated at 13, Fig. 7, the other half being correspondingly lowered, as at 14.

Figs. 9 and 10 give the outlines of tubes that are closed, and which may be employed instead of the open or slotted tubes herein-

before described. The tubes shown in the last named figures are respectively marked 15 and 16. They will fold the paper in the same manner as the other kind, and the 5 strips 7 need not be used in connection with them, the paper to be folded being simply inserted by means of a metallic tape or other convenient tool.

Having thus described my invention, what 10 I claim, and desire to secure by Letters Patent of the United States, is:

1. In a paper folding machine, a die of tubular form having opposed walls, said tube being longitudinally creased so as to 15 gradually fold a web of paper longitudinally when said web is passed through the tube, and a second tube corresponding to the first tube and having its bent sides fitting into the corresponding depression of said first tube.

2. In a paper folding machine, a pair of opposed relatively inverted dies, each comprising a tube longitudinally creased to provide a V-shaped channel having opposed outer and inner walls, the inner walls extending inwardly from the free edges of the outer walls and having their free edges spaced to form a slot or passage, said dies being arranged in intermeshing relation, 25 and strips extending through the respective dies and covering the slots or passages thereof.

3. In a paper folding machine, a die comprising a longitudinally creased tube forming a V-shaped channel having opposed inner and outer walls, the free edges of the inner walls being spaced to form a slot, and a strip extending through the channel and covering said slot.

4. In a paper folding apparatus, a longitudinally creased tube forming a V-shaped channel, having opposed outer and inner walls, said inner walls having their free edges spaced to form a slot, and a strip 45 movably fitted within the channel and covering said slot.

5. In a paper folding apparatus, a die comprising a longitudinally creased tube forming a V-shaped channel, having opposed inner and outer walls, the inner walls having their free edges spaced to form a slot, and a pliable removable strip extending through the channel and covering said slot.

6. A paper folding apparatus comprising two series of oppositely creased, converging and intermeshing tubes, the outer half of the creased part of one tube on either side standing above the other tubes.

7. In a paper folding machine, a die of 60 tubular form having opposed walls, said tube being made flat at the feed end and bent centrally and longitudinally toward the other end so as to operate gradually to fold a web of paper centrally and longitudinally 65 when the paper is passed through the tube,

and a second tube corresponding to the first tube and having its bent sides fitting into the corresponding depression of said first tube.

8. In a paper folding machine, the combination of parallel series of dies, each die in each series comprising a tube flattened at the feed end and having opposed walls, 70 said tube being bent longitudinally to cause its opposite edges gradually to approach each other and said tubes along their bented portions being substantially V-shaped in cross section and the bent sides of the tubes in one series fitting into the corresponding depressions in the other series.

9. In a paper folding apparatus, a longitudinally creased tube providing a V-shaped channel open at one side, and a removable strip of pliable material extending through the channel and covering the open side 85 thereof.

10. A paper folding and interleaving apparatus comprising opposed paper receiving tubes having forming surfaces for independently folding separate webs of paper 90 and maintaining the same in separated relation during the folding action, said tubes being relatively arranged to interleave the webs at their delivery ends.

11. A paper folding and interleaving apparatus comprising two series of tubes adapted each to receive and separately fold a web of paper previously and preparatively to interleaving, the tubes of one series being creased oppositely to and meshing with 100 the tubes of the other series, and said tubes having their delivery ends arranged to interleave the folded webs discharging therefrom.

12. In a paper folding apparatus, two 105 series of dies of duplicate construction, each having opposed forming walls, the forming walls of the respective series of dies being adapted and relatively disposed to fold a corresponding number of moving webs in 110 opposite directions and to maintain the same separated during the folding action, and the walls of the two series of dies being arranged to intermesh with their discharge portions disposed to deliver the series of 115 folded webs in interleaving relation.

13. In a paper folding apparatus, two 120 series of superposed dies having relatively inverted V-shaped channeled walls adapted to reversely fold a corresponding number of webs into similar form, said series of dies being relatively arranged to maintain the webs separated during the folding action, the walls of the series of dies being arranged to break joint and intermesh so as to deliver the series of reversely folded webs in interleaving relation.

14. In a paper folding apparatus, two 125 series of tubular dies adapted to fold a series of moving webs in opposite directions, said 130

series of dies being relatively arranged to maintain the webs separated during the folding action and to interleave the webs as they issue therefrom.

5 15. In a paper folding apparatus, two series of opposed stationary dies adapted to fold a series of moving webs in opposite directions, said series of dies being relatively arranged to maintain the webs separated

during the folding action and to deliver the 10 folded webs in interleaving relation.

In testimony whereof I affix my signature in presence of two witnesses.
